UNITED STATES PATENT OFFICE

2,562,469

STRETCHING AND TACKING IMPLEMENT

Charles M. Lindstrom, Westerly, R. I., assignor
to Bostitch Inc., Stonington, Conn., a corpora-
tion of Rhode Island

Application May 27, 1949, Serial No. 95,645

10 Claims. (Cl. 1—45.6)

1

This invention relates to stapling implements or tackers, so-called, for fastening strip-materials to fixed surfaces or other objects and particularly to a combined work-gripping and stapling or tacking implement for seizing and holding the strip-material in a desired position while driving staples therethrough to fasten it in place.

One object of the invention is to provide a manually-operable implement embodying stapling or tacking mechanism of any suitable type and having combined therewith means by which the work, such as a strip of material, may be gripped adjacent its edge, drawn into place or stretched on a surface and held during the stapling or tacking operation.

Another object is to provide an implement having plier-like means which may be held and actuated by one hand of the operator to cause the gripping means to seize the work for positioning it while leaving the operator's other hand free for manipulation of the staple-driving or tacking mechanism.

Another object is to provide an implement of the type specified in which the plier-means may be operated first to grip the strip of material or other work with the staple-applying mechanism locked against operation and embodying manually-operable means for actuating the staple-driving means which is releasable for operation after the strip-material has been gripped by the plier-actuated means.

Another object is to provide an implement of the type indicated embodying material-gripping means and staple-applying means combined in a single unit of simple construction, economical to manufacture and proof against derangement or getting out of order.

Further objects of the invention are set forth in the following specification which describes the implement as embodied in a preferred form of construction illustrated by the accompanying drawings. In the drawings:

Fig. 1 is a side elevational view of the complete implement shown with its gripping jaws open and the staple-applying means locked against operation;

Fig. 2 is a longitudinal sectional view of the implement showing the parts thereof in the same relationship as in Fig. 1 and illustrating a strip or refill of staples being applied to the magazine;

Fig. 3 is a side view of the implement showing the manner of its operation for gripping and stretching a strip of material for fastening it to a fixed surface;

Fig. 4 is a similar side view showing the manually-operable means as having been actuated with the staple driven through the material and into the surface therebeneath; and

2

Fig. 5 is a front elevational view of the implement.

The present implement is generally similar to that illustrated and described in my United States Letters Patent No. 2,461,165 or February 8, 1949, as regards its staple-applying mechanism and the means for feeding the staples thereto. Otherwise, it differs materially from the implement disclosed in the patent referred to, particularly since the staple-applying mechanism is normally locked from operation and adapted to be actuated only after the jaws of the gripping means have been closed to grip the material to be fastened.

The present implement embodies certain elements of the device of the patent referred to above comprising a hollow magazine-arm 2 of channel-shape for containing a supply of staples and an overlying lever 3 of inverted channel-shape pivoted thereto by a transverse pin 4 and carrying the staple-driver 5 at its forward end. The magazine 2 encloses a staple-core 6 extending longitudinally within its interior for supporting U-shaped staples straddled thereacross, and a pusher 8 is slidable along the core and urged forwardly thereon by means of a coiled spring 9 to feed the staples to the driving means; these parts not being shown or described more in detail in the present specification as they are of conventional type and well known to those versed in the art.

Connected to the forward end of the hollow arm or lever 3 is the staple-driver 5 of blade-like construction and adapted to reciprocate vertically in a narrow guideway or throat 10 at the forward end of the core 6 in accordance with the usual arrangement. A bowed spring 12 fastened to the under side of the top wall of the arm or lever 3 bears against the edges of the side walls of the magazine-arm 2 to normally maintain the lever raised to the position shown in Figs. 1 and 2 with the lower edge of the driver 5 elevated above the top of the staple-core 6. The upward movement of the lever 3 under the action of the spring 12 is limited by means of detent-projections 13 projecting inwardly from its sides and engaging with lugs 14 on the sides of the arm 2 at its forward end, see Figs. 1 and 2. The detent-projections 13 may be formed by strips of the metal sheared from the sides of the lever 3 and punched or forced inwardly, while the lugs 14 project rearwardly from upstanding portions of the magazine-arm 2 as more particularly described in my patent referred to above.

As in the machine of my Patent No. 2,461,165, referred to above, the arm or lever 3 is provided with an opening 15 in its top wall, see Fig. 2, through which a stick S or refill of connected staples s may be loaded into the magazine-arm 2 after previously supplied staples have been ex-

hausted therefrom. For this purpose the staple-pusher 8 may be withdrawn against the action of its spring 9 by means of a slideable member 16 which also serves as a cover for the magazine overlying the heads or crossbars of the staples to prevent them from riding up on the core 6. The cover-member 16 has a longitudinally-extending slot 17 in its top through which a hook-like lug 18 on the staple-pusher 8 projects to adapt it to be engaged by the forward end of the slot when the cover is drawn out at the rear of the magazine-arm to retract the staple-pusher. The cover 16 is held in its forward position by locking means, not herein shown, and maintained in retracted relationship by frictional engagement with the spring 12 to overcome the force of the pusher-spring 9.

As so far described, the elements of the present implement are substantially identical with those disclosed in my prior patent referred to above. The gripping means of the implement for seizing a strip of fabric, such as floor-covering, screen-cloth or other material, are constructed as next described. As shown in Figs. 1 and 2, the bottom wall 21 of the arm 2 is scored or serrated at its forward end to form a series of sharp teeth 22. The toothed portion 22 of the arm 2 forms the upper jaw of the gripping means of the implement, while the lower jaw 23 is embodied in a separate arm 25 of hollow construction having its sides overlapping the sides of the magazine-arm 2 and pivoted at its rearward end on the pivot-pin 4. The arm 25 is of channel-shape with its jaw portion 23 formed of hardened metal inserted into its end and welded or otherwise secured thereto. The upper face of the jaw 23 may be serrated to form teeth 24.

The jaw 23 is adapted to be moved towards the serrated jaw-section 22 of the arm 2 by swinging the arm 25 upwardly under the force of a manually-operated lever 26. The lever 26 is pivoted on a transverse-pin 27 projecting through the sides of the arm 25 and frictionally held in place by means of the looped end 28 of a spring 29. The spring 29 has its rearward end bearing against the under side of the magazine-arm 2 with its bowed portion engaging against the bottom wall of the jaw-arm 25 to normally maintain the latter depressed below the magazine-arm. The lever 26 has a handle-portion 30 of hollow convex shape projecting downwardly in inclined relation below the jaw-member 25 while its upper portion is bifurcated to provide a pair of arms 31 projecting into the hollow of the arm or lever 3 adjacent its side walls, see Figs. 1 and 2. The ends of the arms 31 are formed with hook-like portions 32 engaging around studs 33 projecting inwardly from the sides of the lever 3 with flanged heads 34 at their ends. Rearwardly of the openings in the hook-portions 32 the edges of the arms 31 are shaped with cam-faces 35 designed to operate with mechanical advantage when the handle 30 of the lever 26 is pressed upwardly to rock the jaw-member 25 toward the magazine-arm 2 to close the jaws 22 and 23; this arrangement being similar to that described in my prior patent referred to above.

It will be understood that manual movement of the lever 26 would normally act to draw the lever 3 downwardly relatively to the magazine-arm 2 to cause reciprocation of the staple-driver 5 for driving the foremost staple from the magazine. However, the staple-driving operation must be delayed until the lever 26 is actuated to close the jaws 23 to grip the material. For this

purpose detent-means are provided to prevent relative movement between the driver-lever 3 and the magazine-arm 2 until the jaws have been closed and the material gripped and drawn into place as represented in Fig. 3 of the drawings. The detent-means for preventing movement of the lever 3 with respect to the arm 2 is in the form of a pivoted element 40 which functions initially as a latch to lock these parts against such movement. The latching element 40 is of hollow construction, see Fig. 5, comprising a pair of parallel arms 41 pivoted on studs 42 screwed into the sides of the lever 3. Reaching downwardly from the pivot-studs 42 the arms 41 extend beyond the under side of the lever 3 with their ends adapted to engage lugs 44 which project from the sides of the magazine-arm 2 at the rear of its jaw portion 22. The lugs 44 are formed by the ends of a strip 45 welded or otherwise fastened to the bottom of the magazine-arm 2. A wire spring 46 having a portion coiled around one of the studs 42 is formed with an arm 47 projecting upwardly and forwardly therefrom with its end hooked around the edge of one side wall 41 of the member 40. The opposite arm 48 of the spring 46 reaches upwardly and is hooked around the top of the lever 3, see Figs. 1 and 5, whereby it operates to normally maintain the latching member 40 rocked to the position shown in Figs. 1, 2 and 3 with the ends of its legs 41 in position to engage the lugs 44 on the under side of the magazine-arm 2. A finger or projection 49 on one of the legs 41 of the latching elements 40 is adapted to engage the top of the lever 3 as shown in Figs. 1 and 2 to limit the rocking movement of the element under the force of its spring 46 and maintain it in the relationship last described.

Overlying the top of the latching element 40 is a hand-rest 50 fastened to the top wall thereof by screws 51, see Fig. 2, against which pressure may be exerted to manually rock the member forwardly. The forepart of the member 40 has portions of its side arms 41 folded inwardly to provide abutments 52, see Fig. 5, adapted to strike against the top of the lever 3 to rock it downwardly on the arm 2 to reciprocate the driver 5 for driving a staple into the work after the strip-material has been gripped between the jaws 22 and 23. It will be understood that downward pressure on the hand-rest 50 of the member 40 rocks the latter first to release the ends of its arms 41 from the lugs 44 to allow the lever 3 to be actuated as above described, this operation of the member 40 usually being accomplished by striking the hand-rest 50 with the fist. The method of operation of the complete implement is explained as follows:

To prepare the implement for operation the staple-pusher 8 is retracted by drawing back the cover-member 16. A strip or refill S of staples s is then loaded in the magazine 2 by inserting it through the latching element 40 and down through the opening 15 in the top of the lever 2 to rest on the core 6. The staple-pusher 8 may then be released for sliding the staples s forwardly on the core 6 to position the foremost one in the throat 10 beneath the driver 5.

The implement may be gripped in the hand with the palm overlying the top of the lever 3 and the fingers looped under the handle 30 of the lever 26. The lower jaw 23 may then be inserted under the strip of material M to be tacked or fastened in place and by rocking the lever 26 upwardly in the manner of pliers the jaws 22

and 23 are brought together to seize the material adjacent its marginal edge as shown in Fig. 3. With the strip-material M thus gripped in the implement it may be drawn along the surface to which the material is to be fastened and stretched if necessary, as for tacking fur-pelts to a mounting board, laying floor-coverings and in stretching silk-screens across the sides of a frame. With the implement held in one hand the operator's other hand may be pressed down against the hand-rest 50, or the fist used to strike a sharp blow thereagainst, to operate the lever 3 to drive a staple through the material and into the surface of the floor or a wooden frame F indicated in Fig. 4. Under the initial force of the blow on the hand-rest 50 the latching element 40 will be rocked about the pivot-studs 42 in counterclockwise direction to cause the ends of its legs 41 to swing clear of the lugs 44 on the magazine-arm 2. Immediately the ends of the legs 41 of the latching element 40 are freed from engagement with the lugs 44 on the arm 2 the element will continue its rocking motion to contact the abutments 52 on its fore part with the top of the lever 3 so that thereafter the force of the blow will rock the lever downwardly, thereby reciprocating the staple-driver 5 down through the throat 10, see Fig. 2, to drive the foremost staple through the material M and into the surface on which the strip is to be fastened, as shown in Fig. 4. Upon release of the operator's hand from the rest 50 the lever 3 will be allowed to swing upwardly under the force of its spring 12 and as the ends of the legs 41 on the latching element 40 slide upwardly across the lugs 44 the latching element will be rocked back into locking position shown in Figs. 1 and 2 to again prevent relative movement between the lever 3 and the stapling arm 2. Thereupon, the handle lever 26 may be released to open the jaws 22 and 23 to provide for gripping the strip at another point along its edge. While the implement is illustrated in Figs. 3 and 4 as gripping the strip-material M at a considerable distance inwardly from its edge, the extent to which the strip may be inserted in the jaws is variable and in most instances the material may be gripped close to its marginal edge.

As the parts of the implement are returned to inoperative position with the lever 3 and magazine-arm 2 locked against relative movement the staple-driver 5 will be held in elevated position above the staple-core 6 so that the next staple in the strip S can be fed forwardly by the pusher 8 to locate it under the lower edge of the driver for the next driving operation.

It will be observed from the foregoing description that the present invention provides an implement of great utility for gripping and tacking flexible materials to fixed surfaces or other objects such as stretching fur-pelts, animal skins and the like and fastening them to a mounting board, laying carpets, fastening silk-screens to frames, and for many other similar purposes.

While the implement is herein shown and described in a preferred form of construction it is to be understood that modifications may be made in the structure and arrangement of its parts without departing from the spirit or scope of the invention. Therefore, without limiting myself in this respect, I claim:

1. In an implement for gripping and stretching sheet-material and thereafter fastening it to other objects comprising a magazine for containing fasteners, said magazine having a jaw

formation at its forward end, a fastener-driver for driving the fasteners from the magazine and into the work, and means for operating the fastener-driver, the combination therewith of a jaw movable towards the magazine to grip a strip of material therebetween, a lever for operating said jaw, and detent-means engageable with the fastener-driver operating means for preventing operation of the fastener-driver during the operation of the jaw for gripping the material.

2. In an implement for gripping and stretching sheet-material and thereafter fastening it to other objects comprising a magazine for containing fasteners, said magazine formed to provide a jaw at its forward end, a fastener-driver for driving the fasteners from the magazine and into the work, and means for operating the fastener-driver, the combination therewith of a jaw movable towards the magazine to grip a strip of material therebetween, means for operating said jaw, and detent-means engageable with the fastener-driver operating means to prevent operation of the fastener-driver during the movement of the jaw, said detent-means being manually releasable to permit operation of the fastener-driver.

3. In an implement for gripping and stretching sheet-material and thereafter fastening it to other objects comprising a magazine for containing fasteners, said magazine provided with a jaw at its forward end, fastener-driving means for driving the fasteners from the magazine and into the work, and manually-operable means for operating the fastener-driving means, the combination therewith of an arm pivoted to said magazine and provided with a jaw for cooperation with the jaw thereon, and detent-means normally engaged with said manually-operable means for operating the fastener-driving means for preventing operation of the fastener-driving means while the jaws are being closed to grip the material, said detent-means being releasable to permit operation of the fastener-driving means to drive a fastener into the work at a point in advance of the jaws.

4. In an implement for gripping and holding sheet-material and fastening it in place comprising a magazine for containing staples, said magazine having a throat at its forward end and a jaw on its under side, a lever pivoted to the magazine and carrying a driver for driving the staples through the throat and into the work, the combination therewith of a latching member having a hand-rest, said latching member being manually movable to operate the driver-carrying lever, detent-means for engaging said latching-member to lock said driver-carrying lever from movement relatively to the magazine, an arm having a jaw for cooperation with the jaw on the magazine, and a second lever for swinging said arm to carry its jaw toward the jaw on the magazine to grip the material, said latching member being manually releasable from the detent-means to adapt it to operate the driver-lever to drive a staple after the jaws have gripped the material therebetween.

5. In an implement of the character specified comprising a hollow magazine for containing a supply of staples, said magazine formed with a throat through which the staples are driven and provided with a jaw on its under side, and a driver reciprocable in the throat of the magazine for driving the staples into the work, the combination therewith of a lever for recipro-

eating the driver, a latching member pivoted to said lever and having a hand-rest for operating the lever to actuate the driver to drive a staple, detent-means for normally engaging said latching member to prevent operation of the staple-driver, an arm pivoted to the magazine and formed with a jaw at its end for cooperation with the jaw on the magazine to grip the material therebetween, and a lever for swinging the arm towards the magazine to grip the material between the jaws, said latching member being manually releasable from the detent-means to permit reciprocation of the staple-driver to drive a staple into the work after the jaws have been closed to grip the material.

6. In a plier-like implement for gripping and stretching strip-material and fastening it to a surface comprising a magazine for containing staples, said magazine having a throat through which the staples may be driven and a gripping jaw on its under side, a lever movable relatively to the magazine, a driver reciprocable by said lever in the throat in the magazine to drive the staples therefrom, the combination therewith of an arm pivoted to the magazine and formed with a jaw at its end for cooperation with the jaw on the magazine, a second lever pivoted to said arm and having means connecting it to the driver-lever for moving said arm to close the jaws, and a latching member pivoted to the driver-lever and engageable with detent-means on the magazine to prevent relative movement between the driver-lever and the magazine, said latching member being rockable to release it from the detent-means on the magazine and having a hand-rest to adapt it to be moved by the pressure of the hand to actuate the driver-lever to reciprocate the driver and drive a staple into the work after the material has been gripped by the jaws.

7. In an implement of the character specified comprising a magazine for containing U-shaped staples and provided with a throat through which the staples are driven, a driver reciprocable in the throat of the magazine for driving the staples therethrough, and a pivoted lever for reciprocating the driver, the combination therewith of an arm pivoted to the magazine and formed with a jaw for cooperation with the under side thereof to grip a strip of material therebetween, a hand-lever pivoted to said arm and connected to the driver-lever to swing the arm to close its jaw against the magazine, a latch pivoted to the driver-lever, detent-means on the magazine engageable by the latch to prevent relative movement between the driver-lever and magazine, and a spring for normally maintaining the latch engaged with said detent-means, said latch being manually operable to release it from the detent-means and having a hand-rest for applying a force to move the driver-lever toward the magazine to drive a staple therefrom.

8. In an implement of the character specified having a hollow magazine for containing staples with a throat at its end through which the staples may be driven into the work, a lever pivoted at one end of the magazine and adapted to swing relatively thereto, and a staple-driver connected to said lever for reciprocation in the throat of the magazine, the combination therewith of a latching member pivoted to the driver-lever and engageable with detent-means on the magazine to prevent movement of the driver-lever, said latching member being manually

rockable on the driver-lever to release it from the detent-means and operable when so released to move said driver-lever to reciprocate the staple-driver, an arm pivoted to the magazine and formed with a jaw cooperating with the bottom of the magazine to grip a strip of material therebetween, resilient means for normally maintaining said arm with its jaw spaced from the magazine, and a lever pivoted to the arm and engageable with means on the driver-lever to move the arm to close the jaws for gripping a strip of material therebetween.

9. In an implement of the character specified comprising a magazine-arm for containing staples and provided with a throat at its forward end through which the staples may be driven, a driver reciprocable in said throat to drive the staples from the magazine and into the work, and a lever pivoted to the magazine to move relatively thereto to reciprocate the driver, the combination therewith of an arm pivoted to the magazine and formed with a jaw for cooperation therewith to grip a strip of material therebetween, a lever pivoted to said arm and formed with a handle projecting downwardly in inclined relation thereto, said lever provided with hooked arms engageable with studs on the driver-lever and having cam-faces cooperating with the studs to apply mechanical advantage to the movement of the arm and jaw toward the magazine, and latching means engageable between the driver-lever and the magazine to prevent relative movement therebetween until the material has been gripped, said latching means being manually releasable to permit movement of the driver-lever and operable by a force applied thereto to move said lever to reciprocate the driver and drive a staple into the work.

10. An implement for gripping and holding sheet material and fastening it in place comprising a magazine for containing staples, a driver for driving the staples from the magazine and into the work, a lever for reciprocating said driver, a latching member pivoted to said lever and provided with a hand-rest, detent-means on the magazine engageable with the latching member to prevent relative movement between the lever and magazine, a spring for rocking said latching lever to engage it with said detent-means, a jaw at the forward end of the magazine, an arm for cooperation with the jaw on the magazine, and a hand-lever pivoted to the driver-lever and pivotally connected to the arm to swing the latter toward the magazine and close the jaws, said latching member being manually rockable to release it from the detent-means and when so released to be moved by the pressure of the hand to swing the driver-lever toward the magazine and actuate the driver to drive a staple therefrom after the jaws have been closed.

CHARLES M. LINDSTROM.
